(57) **CLAIM**

The ornamental design for an air fryer basket, as shown and described.

DESCRIPTION

FIG. 1 is a top perspective view of an air fryer basket according to the design;

FIG. 2 is a front elevation view thereof, to which a back elevation view is identical;

FIG. 3 is a right side elevation view thereof, to which a left side elevation view is identical;

FIG. 4 is a top plan view thereof;

FIG. 5 is a bottom plan view thereof; and,

FIG. 6 is a bottom perspective view thereof.

The portions of the article shown in broken line form no part of the claimed design.

1 Claim, 5 Drawing Sheets
